UNITED STATES PATENT OFFICE

LESTER N. WEBER, OF CHICAGO, ILLINOIS, ASSIGNOR TO AMERICAN REENFORCED PAPER COMPANY, OF ATTLEBORO, MASSACHUSETTS, A CORPORATION OF MASSACHUSETTS

TARPAULIN

Application filed December 4, 1930. Serial No. 499,965.

This invention relates to tarpaulins or waterproof sheets adapted for use as a covering for various objects to protect them from the weather.

5 Tarpaulins as commonly constructed are formed of canvas that is treated to render the same waterproof, and are employed to cover and protect various objects on land and aboard ship; but the canvas required to make 10 a tarpaulin is relatively expensive.

The present invention therefore relates to a modified tarpaulin or covering sheet formed of reenforced waterproofed paper, and this modified tarpaulin may be given any desired 15 width by adhesively securing or otherwise fastening two or more strips of reenforced paper together.

The paper employed in forming the tarpaulin of the present invention may be variously reenforced with either spun or unspun fibres and various coating materials may be 20 employed to render the paper waterproof, but a good practical construction is secured by adhesively securing unspun fibres of long 25 staple between two sheets of paper, and the fibres are preferably laid both longitudinally and transversely of the paper to reenforce the same in both directions.

Canvas tarpaulins are commonly provided 30 with tie loops placed along the edges of the tarpaulin to receive a rope or other means for securing the tarpaulin in place over the object to be protected, and it is desirable to provide the modified tarpaulin or cover of the 35 present invention with similar tie loops. The tie loops are usually sewed to the canvas tarpaulin but it is not desirable to sew the tie loops to the reenforced paper of the present modified tarpaulin, since the perforations 40 formed in the paper by the sewing machine needle will decrease the strength of the paper.

One important feature of the present invention therefore resides in a reenforced paper tarpaulin or cover having the tie loops 45 adhesively secured to the edges of the reenforced paper so that a strong pull exerted on the tie loops will be transmitted to the paper without tearing the latter and in means for excluding moisture from the portions of the tie loops secured to the paper.

A further important feature of the present invention resides in a tie loop having the leg portions of the loop firmly secured together close to the edge of the reenforced paper so that a pull exerted upon either leg of the tie 55 loop will be transmitted directly to the other leg at the edge of the paper to prevent the leg portions of the tie loop from being pulled loose from the paper by a strain exerted laterally to the plane of the paper.

Still a further feature of the invention resides in a reenforced paper tarpaulin having its marginal edges folded over and sealed to the face of the paper to prevent the edge 60 from tearing.

The above and other features of the invention will be hereinafter described in connection with the accompanying drawings which illustrate one good practical form of 65 the invention.

In the drawings:

Fig. 1 is a plan view of part of a reenforced paper tarpaulin and tie loop embodying the features of the present invention;

Fig. 2 is a sectional view taken on the line 2—2 of Fig. 1;

Fig. 3, on a reduced scale, is a plan view of a corner portion of the tarpaulin of the present invention;

Fig. 4 is a plan view of a modified form 75 of a reenforced paper tarpaulin; and

Fig. 5 is a sectional view taken on the line 5—5 of Fig. 4.

The reenforced paper employed in constructing the tarpaulin or cover 1 of the present invention may be variously constructed but is shown in the drawings as formed of two sheets of paper 2 and 3 having secured between them the layers 4 and 5, of relatively straight unspun fibres, one layer of fibres being positioned transversely of the paper and the other layer longitudinally of the paper as shown in Fig. 1.

While various forms of fibres may be employed to reenforce the paper sheet 1, a strong and desirable paper is produced by employing fibres of long staple such as sisal as the reenforcing elements and these fibres are preferably secured to the paper in a straightened condition as shown. Different 95 100

waterproof adhesives may be employed to secure the layers 4 and 5 of fibres between the sheets of paper 2 and 3 and good practical results are secured by using black asphaltum as the binding adhesive for securing the sheets of papers together with the reenforcing fibres therebetween.

It will be apparent that the reenforced tarpaulin of the present invention may be given any desired size by varying the width of the reenforced paper of which it is constructed, or by securing two or more strips of paper together. Only a small portion of the entire tarpaulin has been shown in Fig. 3 of the drawings.

It is important to provide anchoring means at spaced intervals along the edges of the tarpaulin so that the tarpaulin may be tied in place over the object to be protected, and this is accomplished in accordance with the present invention by providing the tie loops 6 at spaced intervals along the sides and ends of the sheet 1.

These tie loops or strips 6 are conveniently formed of woven fabric, but the manner of securing them to the paper so as to produce a strong anchor which will not tear the paper is important, and in the embodiment of the invention illustrated each tie loop 6 has the end portions of its legs 7 and 8 adhesively secured to the opposite faces of the reenforced sheet 1. To further strengthen the construction, a protecting and strain distributing patch 9 which may be constructed of reenforced waterproof paper similar to the sheet 1, is adhesively secured over the end portion of each leg 7 and 8, as will be apparent from the drawings. The patches 9 are preferably made relatively large as shown to help distribute the pull exerted by each tie loop over a comparatively large area of the sheet 1 and to exclude moisture from the portions of the tie loop secured to the sheet. The adhesive used for securing the ends of the tie loop 6 to the paper 1 and for securing the patches 9 over these end portions may be the same as that employed between the sheets 2 and 3, or any other strong durable adhesive may be employed.

While the construction so far described for securing the tie loops 6 to the paper 1, will withstand a strong straight pull upon the loops, a pull exerted upon a leg of the loop laterally to the plane of the paper will tend to pull the same loose from the face of the paper to which it is secured. In order to prevent this the legs 7 and 8 are firmly secured together at the edge of the paper to prevent separation of the legs at this point. This is conveniently accomplished by sewing the legs 7 and 8 together, close to the edge of the paper with one or more rows of stitches 10.

The strength and durability of a tarpaulin formed of reenforced paper may be further

increased in accordance with the present invention by folding the marginal edge portions of the reenforced paper over as indicated by 11 and adhesively securing these folded portions to the face of the sheet as shown in Fig. 4. It may also be desirable to fold the corners inwardly as indicated by 12 and adhesively secure these corners to the face of the fabric.

When the edge portions 11 and corners 12 are folded inwardly the anchoring loops 6 are preferably secured to these folded portions as clearly shown in Figs. 4 and 5, as this will further prevent these loops or straps from tearing the paper.

It will be seen from the foregoing that the reenforced paper tarpaulin or cover of the present invention may be employed in various industries where a relatively large, water proof covering is desired and that the same is sufficiently strong and durable to give good service, while the cost of this reenforced paper tarpaulin is only a fraction of the cost of a tarpaulin formed of canvas.

What is claimed is:—

1. A tarpaulin formed of reenforced, waterproof paper and provided with tie loops along the edges of the paper and each tie loop having its leg portions adhesively secured to the opposite faces of the reenforced paper, and each tie loop having its leg portions firmly secured together at the edge of the paper by fastening means extending through said leg portions and adapted to prevent the leg portions from being pulled apart at this point.

2. A tarpaulin formed of reenforced, waterproof paper and provided with tie loops along the edges of the paper, each tie loop having its leg portions adhesively secured to the opposite faces of the reenforced paper, and each tie loop having its leg portions firmly sewed together at the edge of the paper to prevent separation of the leg portions at this point.

3. A tarpaulin formed of reenforced, waterproof paper and provided with tie loops along the edges of the paper, each tie loop having its leg portions adhesively secured to the opposite faces of the reenforced paper, a protecting and strengthening patch adhesively secured to the paper over each leg portion to exclude moisture therefrom, and each tie loop having its leg portions sewed together at the edge of the paper to prevent separation of the leg portions at this point.

4. A tarpaulin formed of reenforced paper and provided with tie loops each having its end portions adhesively secured to the opposite faces of the paper, and a relatively large protecting patch adhesively secured to the face of the paper over each of said end portions to cover the same and distribute the pull exerted upon the tie loop over a

comparatively large area of the reenforced paper.

5. A tarpaulin formed of reenforced, waterproof paper and provided with tie loops along the edges of the paper, each tie loop comprising a strip of woven fabric having its end portions adhesively secured to the opposite faces of the reenforced paper, a protecting and strengthening patch adhesively secured to the paper over each fabric end portion to exclude moisture therefrom and distribute the pull of the fabric over an increased area of the paper, and means extending through the looped fabric strip adjacent the edge of the paper to prevent separation of the leg portions at this point.

In testimony whereof, I have signed my name to this specification.

LESTER N. WEBER.
